PRESSURE TYPE IRRIGATING APPARATUS

Joseph V. Cariffe, San Marino, Calif.; by decree
of distribution to Eleanor E. Cariffe

Application May 12, 1947, Serial No. 747,473

14 Claims. (Cl. 128—224)

1

This invention has to do with pressure type irrigating apparatus and it is a general object of the invention to provide apparatus of this character which is simple, convenient, safe and dependable.

It is desired under many and varied circumstances to provide apparatus to aid in irrigating or flushing cavities of the body, and it is not uncommon to employ medicaments of various types in the liquids used in such devices. A common form of such apparatus is the ordinary fountain syringe wherein the liquid employed is caused to flow by reason of pressure gained by establishing a head of liquid. The head of liquid desired is usually gained by locating a reservoir of liquid at a suitable elevation. In using such a device it is common to introduce the desired medicament into the reservoir so that it is carried by the liquid handled thereby, but there is no provision for regulating either the quantity or the character of the medicament used and for this reason the apparatus may be misused. Further, such apparatus in addition to being in many cases unsafe to use is cumbersome and the pressure generated is ordinarily limited.

It is a general object of this invention to provide apparatus of the general character referred to in which the pressure delivering the flushing liquid is developed in a generator that can be located wherever convenient and which need not be located at any particular elevation.

It is another object of the present invention to provide apparatus of the character referred to which is safe to use even though a medium is employed for the positive generation of pressure. The apparatus that I have employed involves an open passage through which the liquid is delivered to the applicator and in use an increase of pressure in the generator merely increases the rate of flow of the liquid to the applicator.

Another object of the invention is to provide apparatus of the general character referred to which includes a material receptacle or carrier such as to receive and hold but a limited quantity of material which acts in the apparatus to develop the pressure causing flow of the flushing liquid. With the construction that I have provided the generator is sectional, one section serving to carry the supply of liquid and the other to receive and hold the pressure generating material until such time as the generator is assembled and in operating condition. So long as the sections or parts of the generator are separated no pressure can develop in the liquid and consequent any deposit of pressure generating mate-

rial in the liquid prior to making the generator ready for use is merely dissipated.

Another object of the invention is to provide apparatus of the general character referred to involving few simple parts that are inexpensive of manufacture and very simple to manipulate. My construction involves parts that are easily handled, stored and manipulated and the various parts are all such that they can be readily cleaned so that the apparatus may be quickly maintained in fit condition for use.

The various objects and features of my invention will be fully understood from the following detailed description of typical preferred forms and applications of the invention, throughout which description reference is made to the drawings, in which:

Fig. 1 is a view of one form of the apparatus that I have provided with certain parts broken away to show in section. Fig. 2 is a view of certain of the parts of the apparatus shown in Fig. 1, more particularly the generator and the parts immediately associated therewith, the cap or closure section of the generator being shown with material supported by the carrier which is related thereto, and the body of the generator being shown positioned beneath the closure and ready for application thereto, certain of the parts being shown in section. Fig. 3 is a detailed sectional view taken as indicated by line 3—3 on Fig. 2, showing the control means and showing this means in the closed position. Fig. 4 is a view similar to Fig. 3, showing the control means open. Fig. 5 is a plan view taken as indicated by line 5—5 on Fig. 1, and Fig. 6 is a transverse sectional view taken as indicated by line 6—6 on Fig. 1. Figs. 7 to 10 show another form of the invention wherein Fig. 7 is a view showing the generator with certain of the parts in section and with the closure and body assembled, the material carrier being shown supporting material so that the device is ready for operation. Fig. 8 is a plan section taken as indicated by line 8—8 on Fig. 7. Fig. 9 is a view similar to Fig. 8 illustrating the manner in which the material is manipulated in the course of being applied to the material carrier, and Fig. 10 is a view taken as indicated by line 10—10 on Fig. 7.

The apparatus that I have provided may be used in various manners or for various purposes and is generally useful for the irrigation of various cavities of the body, and it can be used to advantage where it is desired to employ a medicament in the liquid being used in the irrigation. My invention may be embodied in various forms,

and in the drawings I have shown it in two forms which are very much alike and which involve, generally, the same essential elements.

In the form of the invention illustrated in Figs. 1 to 6 of the drawings the apparatus involves, generally, a generator A, a delivery conduit B handling fluid from the generator, an applicator C carried on and supplied by the conduit, control means D controlling flow from the generator to the conduit and preferably serving as a coupling between the conduit and the generator, and a material carrier or support E on one section of the generator to be located within the generator when the sections thereof are assembled and the generator is in condition for operation.

The generator A is a fluid carrier or vessel designed and constructed to handle fluids in the form of liquids and gases. In accordance with my invention the generator is sectional and involves, primarily, two sections, a body 10 and a cap or closure 11. The generator further includes releasable means 12 connecting the cap or closure so that when they are connected or combined they form a closed pressure vessel.

The body 10 involves generally a cylindrical side wall 13 and a suitable bottom 14 which closes the lower end of the body, the upper end of the body being open or unrestricted. It is preferred that the body 10 be formed of a single body of material so that it is a unit and in practice it is desirable that it be made simple, plain and smooth so that it may be easily cleaned and maintained in a sanitary condition. In the drawings I have shown longitudinal ribs 15 on the exterior of the side wall 13 providing parts to aid in gripping the body in the course of operating the generator as will be hereinafter described.

The closure or cap 11 may be a simple lid-like element fitting over or on the top of the body 10 and provided with a marginal portion 16 which carries a sealing ring or washer 17 to be engaged by the upper end 18 of the body so that a pressure tight joint is established between the closure and the body when the parts are assembled. The closure 11, like the body, is preferably a simple, smoothly finished element that can be readily maintained in a clean sanitary condition and in practice I prefer to provide the exterior of the cap or closure with a plurality of ribs 19 whereby the operator may conveniently grip the closure for operation.

The means 12 releasably connecting the closure and body preferably provides a threaded connection between these elements and in the preferred form illustrated in the drawings the means 12 includes a depending flange 20 on the marginal portion 16 of the closure which flange is such as to receive the upper end portion of the body 10. An internal thread 21 or the like is provided on the inner surface of the flange 20 to cooperate with a corresponding thread or like part 22 on the exterior of the body adjacent the upper end 18.

The body 10 of the generator is in the nature of an open-topped container or receptacle made large enough to handle an adequate supply of liquid and it may be provided on the inner side 23 of the wall 13 with a gauge mark 24 or the like, indicating the level to which it is desirable that the body should be filled. With the body 10 filled in the desired manner with liquid such as water the closure is applied thereto by moving the closure and body vertically relative to each other while the body is maintained in an upright

or vertical position. When the closure and body are brought together the means 12 is engaged or set by simply rotating the body and closure relative to each other in the desired manner to bring the top end 18 of the body into sealing engagement with the washer 17 in the closure.

The duct B which I provide handles liquid from the generator and supplies it to the applicator C. The duct is preferably an ordinary flexible conduit such as a rubber hose or the like and it will be understood that it may be of any desired length. However, I will point out that with my construction it is unnecessary to locate the generator remote from the point of use and therefore the conduit B may be considerably shorter than is necessary with ordinary apparatus of this general character.

The applicator C is applied to and carried by the outer end of the conduit B and may in practice be of any desired type or character. In practice I propose that the applicator be of a form or type best suited for the particular purpose to which the apparatus is put, and I contemplate that any suitable or desirable applicator may be used with the other features of my construction.

The control means D controls flow from the generator A to the conduit B and preferably serves as a means by which the conduit is coupled with the generator. The particular form of control means illustrated in the drawings involves, generally, a tubular shell 30 carried by closure 11 preferably centrally thereof, a control stem 31 operating in the shell 30, packings 32 between the shell and stem and various other features as I will hereinafter describe.

In the particular case illustrated the shell 30 is formed by two parts or sections, one an upstanding boss-like part 33 that projects upwardly from the closure and the other a depending or downwardly projecting boss-like part 34 which projects downwardly from the closure, the two bosses forming, in effect, one continuous shell-like structure having a central opening or bore 35.

The stem 31 is carried in the shell 30 and is round in cross section to be slidable or shiftable in the bore 35. The stem has an extension or depending part 36 that extends downwardly a substantial distance below the shell 30 and it has an upper end portion 37 which projects a substantial distance above the shell. An inlet passage 38 enters the extension 36 of the stem and extends upwardly in the stem to a point within the shell. An outlet passage 39 is provided in the stem and extends downwardly into the stem from its upper end through the portion 37 and to a point within the shell and adjacent but spaced from the inner end of passage 38. An outlet port 40 extends radially from the inner end portion of passage 38 to the exterior of the stem and an inlet port 41 extends radially from the inner end portion of passage 39 to the exterior of the stem.

The sealing or packing members 32 are preferably annular packings such as rings carried in the shell 30 so that they are axially spaced a substantial distance apart and so that they both seat in the shell and bear on the exterior of the stem. The bore 35 of the shell is recessed at 42 forming a camber X between the two packings rings 32 which chamber is of considerable axial extent. When the control is closed as shown in Fig. 3, the stem is in an up or elevated position where only the outlet port 40 communicates with the chamber X, while the inlet port

41 is above the uppermost packing ring 32. As the stem is moved downwardly in the shell the inlet port 41 gradually moves past the upper packing ring 32 establishing communication between the inlet port and the chamber X and when the control is fully open the inlet port 41 is in full communication with the chamber X, as shown in Fig. 4. It is to be understood of course that in practice I may provide more than one inlet port 41 and more than one outlet port 10 40, as I have shown in the drawings.

In accordance with the broader principles of my invention the stem may be slid or shifted in the shell in any suitable manner. However, I prefer to provide a means for operating or shifting the stem in the shell which means provides convenient control for the structure. In the case illustrated in the drawings the upper end portion 37 of the stem is somewhat enlarged and continues downward into a counterbore 50 provided in the upper end portion of the shell. The exterior of the stem portion 37 is threaded so that this portion of the stem threads into the counterbore 50 which is correspondingly threaded. An operating projection or handle 51 is provided on the upper end portion of the stem, that is on the upper end or projection portion 37, so that the operator may conveniently rotate the stem causing it to be either screwed up or down in the shell as desired.

The carrier E provided to handle material for use in the apparatus may be a suitable receptacle or support, preferably carried by or from the closure 11. In the form of the invention shown in Figs. 1 to 6 of the drawings the carrier E is a plate-like part or shelf 60 carried by the depending lower end portion 36 of the stem to be a suitable distance below the closure or below the lower end of the depending flange 20 provided on the closure. The shelf-like support 60 may be a disc mounted concentric with the stem and in practice may be of limited diameter and located on the stem to be a limited distance below the closure so that only a limited amount of material can be arranged thereon at any one time.

The structure preferably includes a syphon tube 65 depending from the stem as a continuation thereof and proportioned so that its lower end which is open is located immediately above the bottom 14 when the closure is in place on the cap and the stem is operated to its lowermost position. In the particular case illustrated the syphon tube is formed separate from the stem and the shelf-like support 60 serves as a coupling or connecting means between the stem and the syphon tube. In this case bosses 66 are provided on the shelf-like support 60, the upper boss receiving the lower end of the stem while the upper end of the boss receives the end of the syphon tube.

The stem 31 has a coupling portion 52 adjacent to and extending upwardly from the handle 51. The coupling portion as shown in Fig. 1 of the drawings is a tubular continuation of the portion 37 and may have one or more annular ribs 53 to couple the conduit B to the control means D. When an ordinary conduit such as a rubber hose is employed the end 54 of the hose is stretched over the coupling portion 52 and conforms to the configuration of the coupling formed by the ribs. By thus conforming the shape of the coupling portion the hose is securely attached to the means D and consequently to the generator A.

In using the apparatus a suitable quantity of liquid such as water is placed in the body 10 preferably enough water to reach the indicating mark 24 and suitable material M is placed on the material support E or on the shelf 60 in a manner such as is indicated in Fig. 2 of the drawings. The material M may vary widely in character or composition and in accordance with my invention it involves essentially a material which when brought in contact with water generates pressure or is effervescent. For example, the material may include such materials as any carbonates or bicarbonate reacting with an acid, such as sodium bicarbonate, potassium bicarbonate, and such an acid as citric or tartaric acid. It is to be understood that the material M may include in addition to the pressure generating element suitable medicaments as for instance disinfectants or soothing materials, all as may be desired.

With the body 10 filled to the desired level and the desired material located on the carrier E the generator is assembled by moving the body and closure relative to each other to locate the carrier within the generator above the level of the liquid therein. The means 12 is operated to secure the closure on the body making the generator ready for use. With the desired applicator on the conduit B the apparatus is ready for use and to put it in operation it is merely necessary for the user to tilt the generator so that liquid from the body 10 thereof wets the material M. In practice the user may merely invert the generator momentarily in order to assure full wetting of the material M. With the material wetted the generating action proceeds and the user may operate the means D to allow the desired discharge of liquid through the conduit B for delivery to the applicator C. It will be apparent that by proper composition of the material M the device is safe to use and when in use so that liquid is delivered to the applicator the control means D is necessarily open allowing flow so that excessive pressure cannot possibly be applied to the applicator.

In the form of the invention illustrated in Figs. 7 to 10 the various parts are essentially the same as those above described except that the carrier E' for the material M' is somewhat different. In this form of the invention I provide a keyed engagement or relationship between the carrier and the material to be used so that only a specific or particular material can be handled by the carrier. This is desirable as it prevents unsuitable materials being used in the apparatus. In this form of the invention the carrier is located on the extension 36 of the stem but instead of being a shelf or plate-like element it is in the nature of a cross arm 80 preferably a narrow arm which may have slightly upturned ends 81 as shown in the drawings. Each body of material M' to be used in the apparatus is a wafer-like element provided with a central key opening 82 elongate in form and so shaped and proportioned as to accommodate the cross arm 80 so that a wafer can be slid over the arm when positioned or related thereto as shown in Fig. 9. After having been moved up past the arm the wafer or material M' may be rotated to a position such as shown in Fig. 8 where it will be supported by the arm. It is to be understood that in practice one or more elements or wafers of material M' may be used, as indicated in the drawings.

Having described only typical preferred forms

and applications of my invention I do not wish to be limited or restricted to the specific details herein set forth, but wish to reserve to myself any variation or modification that may appear to those skilled in the art and fall within the scope of the following claims.

Having described my invention, I claim:

1. A structure of the character described including, a gas generator, a conduit carrying an applicator, a control mechanism coupling the conduit to the generator and including two relatively movable parts, one releasably engaged with the generator, the control being operable to control flow from the generator to the conduit, and a siphon tube within the generator carried by one of said parts and depending from the control mechanism into the generator.

2. A portable self-contained structure of the character described including, a gas generator including a unitary body open only at the top and a closure for the top of the body, an applicator, a control mechanism coupling the applicator and generator and operable to control flow from the generator to the applicator, and a material carrier located within the body of the generator and carried by the closure, the carrier including an upwardly faced tray spaced below the closure and carrying gas generating material so it is wetted by liquid carried by the body.

3. A structure of the character described including, a gas generator including a unitary body open only at the top and a closure for the top of the body, an applicator, a control mechanism coupling the applicator and generator and operable to control flow from the generator to the applicator, and a material carrier located within the body of the generator and carried by the closure, the carrier including a cross arm in the body spaced below the closure.

4. A freely portable self-contained structure of the character described including, a gas generator including an open topped body and a closure for the body, an applicator, a control mechanism coupling the applicator and generator and operable to control flow from the generator to the applicator and including a control stem depending from the closure into the body to the lower end portion thereof and open at its lower end to receive fluid from the lower end portion of the body, and a material carrier supported by the depending portion of the stem and located above the opening therein.

5. A structure of the character described including, a gas generator including an open topped body and a closure for the body, an applicator, a control mechanism coupling the applicator and generator and operable to control flow from the generator to the applicator and including a control stem depending from the closure into the body and handling fluid from the body, and a material carrier supported by the depending portion of the stem and including a disc shaped tray.

6. A structure of the character described including, a gas generator including an open topped body and a closure for the body, an applicator, a control mechanism coupling the applicator and generator and operable to control flow from the generator to the applicator and including a control stem depending from the closure into the body and handling fluid from the body, and a material carrier supported by the depending portion of the stem and including an elongate cross arm.

7. A structure of the character described including, a gas generator including an open topped

body and a closure for the body, an applicator, a control mechanism controlling flow from the generator to the applicator and including a control stem depending from the closure into the body and handling fluid from the body, a body of material having a key opening therein, and a key member carried by the stem insertable through the opening and operable to support the body of material in position in the body to be contacted by liquid in the body of the generator upon deflection of the generator from an upright position.

8. A structure of the character described including, a gas generator including an open topped body and a closure for the body, an applicator, a control mechanism controlling flow from the generator to the applicator and including a control stem depending from the closure into the body and handling fluid from the body, a material carrier supported by the depending portion of the stem, and a siphon tube carried by the stem in communication therewith and depending into the lower end portion of the body of the generator.

9. A portable self-contained structure of the character described including, a gas generator having a body open only at its upper end and a detachable closure for the body, a conduit carrying an applicator, and a control mechanism coupling the generator and conduit and including, a shell carried by the closure and a tubular stem in communication with the conduit and carried by the shell to extend therethrough and into the body and movable relative to the shell to control flow from the generator body to the conduit.

10. A structure of the character described including, a gas generator having an open topped body and a closure for the body, a conduit carrying an applicator, and a control mechanism coupling the generator and conduit and including, a shell carried by the closure and a stem carried by the shell and movable relative thereto, the shell having a chamber therein surrounding the stem and the stem having passages entering it from each end and ports from the passages to the exterior of the stem where the port from one passage is movable into and out of communication with the chamber upon shifting of the stem relative to the shell, the port from the other passage being in communication with the chamber when the first named port is in communication with the chamber.

11. A structure of the character described including, a material carrier, a gas generator having an open topped body and a closure for the body, an applicator, and a control mechanism including, a shell carried by the closure and a fluid conducting stem carried by the shell and movable relative thereto to control flow from the generator to the applicator, the stem having an outer end with an operating handle, and having an inner end within the chamber supporting the material carrier within the body.

12. In a device of the character set forth, a generator having a cylindrical wall, a bottom closing the lower end of the generator and a releasable closure for the top end of the generator, a material holder confined to the upper end portion of the generator within said wall and below the closure to be wetted by liquid from the lower portion of the generator upon deflection of the generator from a normal upright position, and means conducting flow from the generator through the closure.

13. In a device of the character set forth, a generator having a cylindrical wall, a bottom closing the lower end of the generator and a releasable closure for the top end of the generator, a material holder confined to the upper end portion of the generator within said wall and below the closure to be wetted by liquid from the lower portion of the generator upon deflection of the generator from a normal upright position, and a tube extending through the closure conducting fluid from the generator and supporting the holder.

14. In a device of the character set forth, a generator having a cylindrical wall, a bottom closing the lower end of the generator and a releasable closure for the top end of the generator, a material holder confined to the upper end portion of the generator within said wall and below the closure to be wetted by liquid from the lower

portion of the generator upon deflection of the generator from a normal upright position, and a tube extending through the closure conducting fluid from the generator and supporting the holder, the tube being vertically shiftable relative to the closure to control flow therethrough.

JOSEPH V. CARIFFE.
